COOLING ELECTRICAL APPARATUS

Emerson Venable, Wilkinsburg, Pa., assignor to
Westinghouse Electric & Manufacturing Com-
pany, East Pittsburgh, Pa., a corporation of
Pennsylvania

Application September 27, 1940, Serial No. 358,649

7 Claims. (Cl. 175—361)

This invention relates to electrical apparatus, and, more particularly, to cooling electrical apparatus by means of solid materials.

In the manufacture of electrical apparatus, the design and construction are influenced by the fact that the electrical members are subject to heating when in use. Provision must be made to dissipate the accumulated heat for efficient operation of the apparatus. The cooling of apparatus that has substantially no moving parts, such, for example, as transformers and reactors, introduces a problem which is different from that found in rotating apparatus.

Heretofore the cooling of electrical apparatus, such as transformers, has been effected by means of fluids, particularly refined petroleum oils and halogenated hydrocarbons. These hydrocarbon fluids are frequently preferred to other cooling agents, since they also contribute to the insulation of the electrical elements and thereby perform a dual function.

These cooling fluids perform the function of cooling by convective heat transfer. The thermal conductivity through the fluids is so low that it may be considered negligible for practical purposes. Accordingly, the design of the electrical elements in the casing enclosing the transformer is influenced by the desire to obtain the best convective flow of the insulating liquid in order to keep the temperature within prescribed limits.

Under some operating conditions, petroleum oils deteriorate considerably and fail to function properly. Under arcing conditions, the oil will tend to break down and form combustible gases. In addition, on exposure to air or oxygen, the oil will sludge and form a conducting precipitate. Occasionally, transformers filled with oil have caught fire or even exploded, causing tremendous damage. Consequently, in certain localities where such hazards would be dangerous, oil-filled transformers have been restricted in their application or even prohibited.

It has been proposed to obviate the inflammable characteristics of refined petroleum oil by substituting halogenated hydrocarbons therefor. The halogenated hydrocarbons are much more expensive than the refined petroleum oils employed in transformer constructions and are made use of only when the cost consideration is surmounted by the increased advantages obtained by the lesser fire hazard.

In a few installations, air or gas-cooled trans-
formers have been made use of in order to avoid
these defects of liquid cooled apparatus. For ex-
ample, in subways and in other localities where

the presence of many persons is unavoidable, it has been common to employ transformers cooled by air due to the fact that the fire or explosion hazard is eliminated. However, air contains moisture and chemically reactive gases, such as carbon dioxide, hydrogen sulphide and oxygen. These constituents, which are commonly present in air in relatively great quantities, are not desirable for electrical and chemical considerations. It is necessary to place a much heavier solid insulation upon the coils of air-cooled transformers in order that the coils will safely carry their load without failure. The insulation and the characteristics of air result in a greater thermal gradient to dissipate a given amount of heat from the electrical elements.

In all apparatus employing oils or air, the design emphasis must be placed upon providing suitable passageways and spaces within the electrical members in order to promote the best convective flow of cooling medium. The provision of numerous spaces and passageways does not coincide with the most efficient electrical operation of the electrical apparatus or the most economical arrangement of the material for a given capacity. It is necessary to compromise the various requirements in order to obtain satisfactory operating results.

It is a purpose of this invention to replace fluid cooling mediums by dielectric solids which will function to dissipate the heat generated by the electrical elements by conduction alone. According to this invention, discrete crystalline particles or granules of solid inorganic salt or mineral material are used as a filling about the electrical elements to conduct or carry away the heat generated. The filling also acts as an insulation and results in a better electrical performance of the apparatus.

The object of this invention is to provide for cooling electrical apparatus.

A further object of this invention is to provide for insulating and cooling electrical apparatus by employing a dielectric mineral filler.

Other objects and advantages will appear more fully from the following detailed description taken in conjunction with the accompanying drawings which are representative of one embodiment of the invention, and in which:

Figure 1 is a vertical section of a transformer according to the invention;

Fig. 2 is an enlarged section of a portion of the apparatus of Fig. 1; and

Fig. 3 is a graph illustrating the improved heat

transfer obtained through the use of the selected mineral filler.

The cooling of electrical apparatus by means of liquids or gases depends almost entirely upon convective heat transfer. The thermal conduction of heat by liquids or gases is almost negligible in comparison with the convective heat transfer. For example, petroleum has an average thermal conductivity of about 0.00035 calorie per second per square centimeter per centimeter thickness per degree centigrade. By comparison, copper has about 3,000 times and fluorite has about 80 times this thermal conductivity.

For the purposes of this invention, it is proposed to use a dielectric composed of loose crystalline granules of minerals that have thermal conductivities of 50 times or more than that of oil. While it is a general rule that substances which have good thermal conductivity also have good electrical conductivity, this rule does not apply in the case of a few critical minerals which it is preferred to employ in this invention. Among these minerals are fluorite (CaF_2), halite (NaCl), villiaumite (NaF), potassium fluoride (KF) and sylvite (KCl), which have thermal conductivities of 0.026, 0.0168, 0.025, 0.016 and 0.0166 calorie per square centimeter per degree centigrade per inch thickness, respectively.

In addition, these five minerals have an exceedingly high electrical resistivity up to the temperature of fusion. For example, at room temperature, the electrical resistivity of these minerals is of the order of 10^{17} ohms per cubic centimeter. At 100° C. the resistivity is of the order of 10^{13} ohms, and at 500° C. the resistance is of the order of 10^7 ohms.

The mineral salts fluorite, halite, villiaumite, potassium fluoride, and sylvite are given as examples of materials presenting the required fundamental thermal and electrical characteristics for a good filling for electrical equipment. Other materials having a thermal conductivity of 0.01 calorie or better in c. g. s. units and electrical resistance of the order above specified will be satisfactory.

It is a well-known fact in the transfer of heat that frequently the greatest resistance to heat flow is at the contact surfaces between two different elements in the path of the heat flow. Certain minerals have inherent high specific thermal conductivity, quartz, for example, but with a poor cleavage structure and the surface contact between adjacent particles is so poor that the overall thermal conductivity is much lower than that of a mass of other minerals with lower heat conductivity, but with better surface characteristics. It is believed that due to the poor cleavage of the quartz, which gives a conchoidal fracture, the contact between adjacent quartz particles is substantially a point-to-point contact with a consequent poor heat transfer.

The best overall heat transfer between a plurality of crystals of mineral will be had when the crystals are simple geometrical shapes with substantially all plane faces or with plane cleavage fractures. Cubic or tetragonal crystals will pack together closely with plane face to plane face contact. Other simple geometrical solids will exhibit similar packing characteristics. A body of crystals so packed will exhibit the lowest thermal gradients. Such a crystalline structure is present in fluorite, halite, villiaumite, potassium fluoride, and sylvite, all of which crystallize in the cubic or isometric system and have plane cleavage surfaces with regular angular relation-

ship. Accordingly, the overall thermal conductivity of a mass of these five salts is high. Various other inorganic and mineral substances which meet these requirements of crystalline shape may be used as a cooling filling.

In employing a dielectric filler comprising such crystals, a further advantage obtains in that a greater apparent density or packing coefficient is had with this type of crystal. A given volume 10 was successively filled with crushed quartz and crushed fluorite passing through the same mesh screen. The packing coefficient of the fluorite was 89%, whereas that of quartz was only 80%. This means that the fluorite filled all the space 15 more completely than did the quartz, and consequently fewer voids were present. In addition, such a high packing coefficient necessarily results in a considerable amount of crystals having plane surfaces contacting plane surfaces on adjacent crystals. Therefore, fluorite crystals 20 should give better cooling of electrical apparatus than a quartz filling.

Referring to Fig. 3 of the drawings, there is illustrated the thermal performance of masses of 25 three different materials placed within a container and subjected to heating for a given period of time and cooling thereafter. The three different materials that were employed as a loose filling around the electrical member for the purpose of this test were fluorite, air and quartz. The temperatures were taken at a position 30 remote from the heating element to determine the overall thermal conductivity of the filling material. It will be noted that the fluorite indicated 35 the maximum temperature at the remote point. In other words, its conductivity exceeded that of either quartz or air. It will be noted that the fluorite has a decided advantage over air as a thermal conductor as far as cooling efficiency is concerned. Quartz has a higher conductivity as a mineral, but, due to its poor crystalline structure, was much inferior to either fluorite or air as a heat conductor.

A transformer having electrical elements which 45 are subject to heating when in use, when cooled by means of the dielectric mineral filling according to this invention, will have its heat dissipated most effectively if certain refinements in the design are made. It will be appreciated that heat 50 must be transferred from the electrical elements, which will be covered with a certain amount of solid insulation, to the adjacent granular or crystalline mineral body. The optimum heat transfer will occur if the mineral crystals contact the 55 electrical elements at plane faces or flat surfaces with as great a proportion as possible of the element being covered. This will insure that a low thermal gradient occurs at this point. Since the 60 heat outflow areas are necessarily a minimum at the electrical element surfaces, it will be advantageous to increase the flat face contact and the areas in contact between the mineral with the electrical elements in order to obtain the best overall heat conduction.

65 Finally, the transformer enclosure or casing will receive the heat after it has passed through the mineral body and will deliver it to the atmosphere. The transformer casing should be constructed so that the flat crystal faces will contact flat surfaces on the transformer casing for best thermal heat transfer. All these considerations 70 are taken advantage of in the design of the apparatus shown on the drawings.

Referring to Fig. 1 of the drawings, the trans- 75 former 18 comprises a bottom plate 12, side walls

14 having flat surfaces and a cover 16. The transformer is hermetically sealed by means of welding 18. The cover 16 has an aperture 21 for the introduction of the loose granular mineral dielectric. The aperture 21 may be tightly sealed by means of a cover 20 and appropriate sealing means. Attached to and extending through the cover 16 are two terminal bushings 22 and 24. Current passes by means of the terminal bushings to the conductors 26 connected with the electrical elements within the transformer casing.

Operating electrical members within the casing comprise a core 30 of magnetic material, preferably in laminated form, and a plurality of conductor pancake coils 32. Insulating bushings 36 are placed about the legs of the transformer on which the coils 32 are wound. Thin insulation 34 is placed about each of the coils 32 to provide a certain amount of electrical insulation.

The coils and magnetic core, when placed within a transformer and connected up to the bushings 22 and 24 with the cover 16 in place, are filled with the granular dielectric mineral filling selected from one or more of fluorite, halite, sodium fluoride, potassium fluoride, and sylvite hereinbefore described. There are several methods of insuring a thorough filling of the transformer with the mineral to obtain the best packing. It is possible to vibrate the casing 14 with an electromagnetic vibrator to insure as complete filling as possible when the mineral granules are being poured in through opening 21. The coils 32 may be energized with alternating current, and a certain amount of vibration will be generated to assist in a good placement of the mineral granules in and around the coil and core.

In some instances, it may be more satisfactory to place selected mineral particles between the coils before assembling the electrical elements together. Referring to Fig. 2 of the drawings, it will be noted that the coils 32 are separated by closely packed layers of salt or mineral 42. These may be fitted in by hand before the apparatus is assembled. A convenient method of doing this will be to take an insulated pancake coil 32, apply it to the sleeve 36 in a vertical position, and to apply one or more layers of salt crystals of uniform shape. A dense and homogeneous salt filling will be effected. A second coil 32 may be slipped over the end of the insulating tube 36 and rested on the layers of crystals. Additional layers of salt crystals may be placed upon the second coil 32. Tape may be placed around the periphery of the salt layers to prevent their displacement as the operation is continued. When a complete stack of coils sufficient for one leg of the transformer has been built up in this manner, the leg of the core of the magnetic material may be inserted into the insulating sleeve 36. This may be readily accomplished due to the fact that the legs of the core of magnetic material are generally cut out in L-shape punchings and assembled one by one into cores of desired thickness. When both legs of the core of magnetic material have been inserted into their respective coil structures, the entire unit may be brought together and assembled within the transformer casing. A loose salt filling may then be poured in through aperture 21 in the cover 16 until the casing is filled to the selected level.

For best results, the walls 14 of the transformer casing should be made so as to present flat surfaces to the salt or mineral filling. A square casing is one possible type of casing for this purpose. Hexagonal and corrugated flat

ribbed casings may also be used for this purpose.

It will be appreciated that the best filling will be had when the loose salt filling 40 consists of crystals all having substantially the same physical dimensions. Controlled crystallization of a saturated salt solution will yield a high percentage of crystals having the same physical dimensions. Close screening of the crystals, however obtained, is another possible way to secure uniformly sized particles.

It is not necessary to employ the natural crystal, but blocks or cubes of any desired physical size to suit the requirements of manufacture may be sawed or cut from large salt masses. In addition, the salt or mineral may be fused and cast into cubes or shapes of the selected dimensions. The fused salt should recrystallize on cooling for good thermal conductivity. The natural crystal will undoubtedly be the least expensive and, where obtainable in the proper size and uniformity of particles, will be preferred on this account.

It will be appreciated that finer crystals, due to their relatively large number for a given volume, may retard heat flow. It would be more satisfactory to employ crystals or grains of large physical size, since the larger particles will have fewer interfaces for the heat to pass through.

In the largest type of transformer, such as used in major electrical systems, the transformer may be filled by laying large size blocks of salt by hand in uniform rows and building up the transformer into a solid and substantially voidless filling. The optimum thermal conductivity will be obtained by a transformer in which the dielectric filling is laid in such a regular manner.

It is preferred to enclose the entire transformer within a casing that is substantially hermetically sealed with respect to the outside air. The entry of moisture into the filling may result in corrosion and deterioration of the magnetic core and other elements, and this it is desired to avoid. To insure that all the moisture is removed when the transformer is filled, the transformer may be heated to a high temperature in order that all of the moisture present will be driven off. A moisture absorbing material, such as calcium chloride, may be placed within the transformer to insure an extremely dry atmosphere for this purpose. Once the thoroughly dried transformer is sealed, however, the contents will be protected from chemical change.

The minerals fluorite, halite, viliuaumite, potassium fluoride, and sylvite have good electrical properties up to very high temperatures. Their resistance is satisfactory even at a dull red heat. A transformer constructed with the mineral or salt filling will be able to withstand tremendous overloads for long continued periods of time without suffering any permanent deterioration. The salt filling is a high grade insulator and will withstand surges which would be serious or even fatal in oil-filled transformers. If flashover or arcing occurs, the mineral does not break down permanently, but at most may fuse. However, once the electrical stress is removed, the filling resolidifies at this place and electrically is as good as it originally was. This self-healing characteristic constitutes a considerable improvement on hydrocarbon material which breaks down permanently and leaves a conducting carbonaceous residue.

The preceding description relates to the preferred embodiment of the invention. Changes

in the modification and in the details of the invention are intended to be included within the spirit and scope thereof, as indicated in the claims.

I claim as my invention:

1. In electrical apparatus, in combination, a solid electrical conductor member subject to heating when in use, a casing enclosing the electrical member, and a dielectric in the casing in direct contact with the electrical member cooperative to transfer accumulated heat to the casing to control the temperature, the dielectric comprising loose granular crystalline parallelepiped shaped solids having a thermal conductivity of 0.01 calorie or higher per centimeter per degree centigrade per square centimeter per second, the granular solids having predominantly flat surfaces and sufficient surface contact with one another, with the electrical member and with the casing to effect a predetermined transfer and dissipation of heat to the casing, the granular solids applied adjacent the electrical member as a substantially voidless body to effect efficient overall thermal conductivity.

2. In a transformer, in combination, electrical conductors and a core subject to heating when in use, a casing enclosing and protecting the electrical conductors and core, and a dielectric in the casing applied directly to the electrical conductors and the core cooperative to transfer heat to the casing to control the temperature, the dielectric comprising loose, granular crystalline parallelepiped shaped solids having a thermal conductivity of 0.01 calorie or higher per centimeter per degree centigrade per square centimeter per second, the crystalline solids having substantially all plane faces, the granular solids having sufficient surface contact with one another along the plane faces, with the electrical conductors and the core, and with the casing to effect a predetermined transfer and dissipation of heat to the casing.

3. Electrical apparatus comprising, in combination, an electrical transformer core and windings subject to heating when in operation, a casing having predominantly flat walls enclosing and protecting the electrical transformer core and windings and an electrical insulating and heat dissipating dielectric filling in the sealed casing, the filling surrounding and contacting the electrical transformer core and windings and contacting the flat walls of the casing, the heat conducting dielectric filling composed of loose, granular crystalline solids having a thermal conductivity of 0.01 calorie or higher per centimeter per degree centigrade per square centimeter per second having predominantly plane surfaces and of simple geometrical shape to provide for a high packing coefficient, and a high proportion of the crystalline solids having plane surface to plane surface contact to effect good thermal conductivity through the dielectric filling to thereby effect transfer of the heat generated by the electrical transformer core and windings to the walls of the casing with a low thermal gradient.

4. Electrical apparatus comprising, in combination, a solid electrical conductor member subject to heating when in operation, a casing enclosing and protecting the electrical member and an electrical insulating and heat dissipating dielectric filling the sealed casing, the filling sur-

rounding and contacting the electrical member and contacting the casing, the heat conducting dielectric filling composed of loose, crushed, granular crystalline solids of substantially the same size, the solids having a thermal conductivity of greater than 0.01 calorie per second per degree centigrade per square centimeter of surface for a thickness of one centimeter and having predominantly plane surfaces and plane cleavage fracture, and of simple geometrical shapes to provide for a high packing coefficient, and a high proportion of the solids having plane surface to plane surface contact to effect good thermal conductivity through the dielectric filling to thereby effect transfer of the heat generated by the electrical member to the casing with a low thermal gradient.

5. Electrical apparatus comprising, in combination, a solid electrical conductor member subject to heating when in operation, a casing for the electrical conductor member, a good heat dissipating dielectric filling surrounding the electrical member, the dielectric filling composed of at least one salt selected from the group consisting of calcium fluoride, sodium chloride, sodium fluoride, potassium fluoride, and potassium chloride, the salt filling composed of a plurality of bodies of simple solid geometrical shape having plane faces to provide for a good packing coefficient and a high proportion of the solid bodies having plane face to plane face contact to provide for a good thermal conductivity to effect removal of the heat from the electrical member with a low thermal gradient.

6. Electrical apparatus comprising, in combination, a solid electrical conductor member subject to heating when in use, a sealed casing for enclosing and protecting the electrical member, and an electrical insulating and heat conducting dielectric filling in and contacting the walls of the casing surrounding the electrical member, the filling composed of at least one salt selected from the group of calcium fluoride, sodium chloride, sodium fluoride, potassium fluoride, and potassium chloride, the salt filling composed of a plurality of bodies of simple, solid geometrical shape having plane faces and a plane cleavage fracture to provide for a good packing coefficient and a high proportion of the solid bodies having plane face to plane face contact to provide for a good thermal conductivity to effect removal and dissipation of the heat developed in the electrical member to the casing with a low thermal gradient.

7. A loose, granular dielectric filling for solid electrical members enclosed in a sealed casing, comprising at least one salt selected from the group consisting of calcium fluoride, sodium chloride, sodium fluoride, potassium fluoride and potassium chloride, the salts being in the form of large crystals and being characterized by a high thermal conductivity and the crystals being of simple geometrical shapes having plane faces and having plane cleavage fracture, to provide for a good packing coefficient in the sealed casing whereby heat is removed from the electrical members and transferred to the casing with low thermal gradients, the filling having good electrical insulating properties at temperatures below the fusing temperature of the salts.

EMERSON VENABLE.
